UNITED STATES PATENT OFFICE

110,571

DESIGN FOR A GREASE CABINET

Ross Kelly McCoy, Oakland, Calif., assignor to
Lincoln Engineering Company, St. Louis, Mo., a
corporation of Missouri

Application July 6, 1937, Serial No. 70,277

Term of patent 7 years

To all whom it may concern:

Be it known that I, Ross Kelly McCoy, a citizen
of the United States and a resident of Oakland,
County of Alameda, State of California, have in-
vented a new, original and ornamental Design
for a Grease Cabinet, of which the following is a
specification, reference being had to the accom-
panying drawing, forming part thereof, in which

Fig. 1 is a front isometric view of the grease
cabinet, showing my design; and,

Fig. 2 is a rear elevational view thereof, on a
reduced scale.

I claim:

The ornamental design for a grease cabinet,
substantially as shown.

ROSS KELLY MCCOY.
